UNITED STATES PATENT OFFICE.

HARRY A. DOUGLAS, OF BRONSON, MICHIGAN, ASSIGNEE TO DOUGLAS & RUDD MANUFACTURING COMPANY, OF BRONSON, MICHIGAN, A CORPORATION OF MICHIGAN.

CIRCUIT-COUPING.

1,173,711.

Specification of Letters Patent. Patented Feb. 29, 1916.

Application filed June 28, 1912. Serial No. 776,217.

To all whom it may concern:

Be it known that I, HARRY A. DOUGLAS, citizen of the United States, residing at Bronson, in the county of Branch and State of Michigan, have invented a certain new and useful Improvement in Circuit-Couplings, of which the following is a full, clear, concise, and exact description, reference being had to the accompanying drawings, forming a part of this specification.

My invention relates to circuit closing switches or extenders and has a number of objects and advantages in view.

My invention has, for one of its objects the provision of a circuit extender having two poles that are insulated apart for connection with a metallic circuit, one of these poles being connected with another and central pole while the other of the first two poles is connected with an inclosing shell.

The invention has for another of its objects the provision of means whereby two component parts of the circuit extender may have two adjustments, one for closing the controlling circuit and the second for opening the circuit before a third adjustment may be reached that permits the separation of the coupled elements of the extender.

The invention has for another of its objects the provision of improved means for holding circuit conducting elements in position.

The invention has for another of its objects the provision of improved coöperating coupling members of a circuit extender or connector in which circuit closing spring contacts are employed.

The invention has other objects and advantages which will be fully explained by reference to the accompanying drawing showing the preferred embodiment thereof and in which—

Figure 1 is a longitudinal sectional view showing one coupling portion and a part of a complementary coupling portion, the two parts being shown as displaced 90° from their proper relative positions for the sake of clearness; Fig. 2 shows separated parts of Fig. 1 in mechanical union in such relative position as to be in open circuit; Fig. 3 is a view similar to Fig. 2 excepting that the parts occupy positions in which the circuit is closed; Fig. 4 is a side view of a part of the structure as it appears in Fig. 2; Fig.

5 is a sectional view on line 5 5 of Fig. 2; Fig. 6 is a side view of a part of the structure as it appears in Fig. 3; and Fig. 7 is a sectional plan view on line 7 7 of Fig. 1. Like parts are indicated by similar characters of reference throughout the different figures.

The invention is herein shown in the form of a connector for coupling circuit sections at intermediate portions of circuits for enabling the transmission of current to distantly located translating devices, such as lamps, though the invention is not to be limited to this adaptation. The device shown includes two main coupling members. One of these members includes an inclosing metallic cylindrical shell 1 provided with insetting spring tongues 2 which are inwardly struck from the shell. The shell constitutes a terminal which incloses a tubular contact terminal 3 all as will be fully hereinafter set forth. The terminals 1 and 3 are, by means of the construction herein-after to be described, adapted respectively for connection with a cylindrical shell-like terminal 4 and a central terminal 5 of a circuit coupling member companion to that which includes the elements 1, 2 and 3. The contact 3 is desirably outwardly sprung pressed by means of the outer one of springs 6, 6¹ which are preferably in the form of two oppositely wound coils so that the coils of each spring are obliquely disposed with respect to the coils of the other whereby neither spring can crowd into the spaces between the coils of the other spring. Pins 7 are carried by the coupling member receivable within the shell 1, these pins being preferably metallic so as to have electrical connection with the cylindrical shell 4. The shell 1 is provided with bayonet slots each having an outlet 8 extending longitudinally of the shell and a lateral continuation of this outlet having portions 9 and 10 upon the same side of the longitudinal portion 8, the portion 10 being sufficiently close to the terminal 3 to maintain the contacts 3 and 5 in engagement when the pins 7 are received by these portions 10, while the portion 9 is so far removed as to prevent the contact 3 from reaching the contact 5 when the pins 7 are received by these portions 9, the contact 3 having a rear flange which is engaged with a stop 11 by means of the outer one of the springs 6, 6¹ for the pur-

pose of preventing the contact 3 from reaching the contact 5 when the pins 7 are received in the slot portions 9. The portions 9 and 10 of the bayonet slot are circumferentially displaced so that the circuit opening and closing adjustment and the uncoupling of the members may be effected by as few relative movements as possible and which movements are as short as may be. The contact spring tongues 2 and the engaging portion of the cylindrical terminal 4 are obviously kept bright to insure good electrical connection, owing to the relative longitudinal movements and the relative 15 rotary movements that occur between the elements 1 and 4. The abutting surfaces of the contacts 3 and 5 are also kept bright due to the relative rotary motion occurring between these elements when the bayonet 20 pins 7 are moved in the lateral portions of the bayonet slots.

It will be observed that the slot portions 9 and 10 project upwardly so that when the pins 7 are received therein the element 25 4 will not be shaken loose, one or the other of the springs 6, 6¹ firmly pressing the pins 7 into the slot portions 9 or 10. When the pins 7 are in the slot portions 10 the outer spring 6 holds these pins 7 in place through the direct intermedium of the terminal 3. When the pins 7 are in slot portions 9 the inner spring 6¹ operates to hold the pins in place through the intermedium of the plug or plunger of insulating material 12 30 which projects through and is in sliding relation with the cylindrical contact 3, this plug 12 having a rear flange that prevents it from being projected clear through the contact 3. The plug 12 has a rear extension 35 that enters the bore of the inner spring to maintain the spring and plug in alinement. When the circuit is established by the device of my invention the springs 2 operate to hold the coupled members in 40 sufficiently rigid relation to prevent rattling. When the circuit is broken the inner spring 6¹ operates through the plug 12 for a similar purpose. The pins 7 are guided from the slot portions 10 to the slot 45 portions 9 or from the slot portions 9 to the slot portions 10 by means of continuations of adjacent slot portions 9 and 10 that are common and which common continuations are defined by a wall portion 13. Passage 50 between adjacent slot portions 8 and 9 is likewise determined by a continuation common to these two slot portions at 14.

The shell 4 contains a plug 15 of insulating material in which terminals 16 are received, this plug 15 also containing the contact element 5 that is in electrical connection with one of the terminals 16, the other of the terminals 16 being in connection with the shell 4, whereby the electrical fitting 65 is adaptable to grounded circuits. The

shell 1 contains a plug of insulating material 17 in fixed relation thereto, the abutment 11 being in fixed relation with respect to the plug 17, this abutment being in the form of a spring barrel closed at its rear end to engage the springs 6, 6¹. An inserting pin 18 is in electrical connection with the shell 1 and projects into line with an aperture 19 extending longitudinally of the plug 17. A similar aperture 20 extends to the rear of the spring barrel 11. The contact terminals 21 and 22 are received respectively within the apertures 19 and 20 and respectively engage the pin 18 and the spring barrel 11 whereby this electrical fitting is adaptable to grounded circuits. These contacts 21, 22 are provided with surrounding annular grooves in which spring washers 23 are received to constitute outer setting flanges, it being preferred to employ the spring washers rather than to form the flange integrally with the contacts to save material and labor. The external surfaces of the contacts 21 and 22 are smooth so as freely to be moved in the openings 19 and 20. Hollow or sleeve nuts 24 have threaded engagement with the plug 17 and butt engagement with the washers 23 whereby the contact terminals 21 and 22 may be forced into tight electrical connection respectively with the elements 18 and 11. These nuts 24 are desirably made of insulating material and being in the nature of sleeves the conducting wires 25 that pass into the contacts 21 and 22 through the nuts 24 are protected thereby.

While I have herein shown and particularly described the preferred embodiment of my invention I do not wish to be limited to the precise details of construction and circuit arrangement shown as changes may readily be made without departing from the spirit of my invention, but

Having thus described my invention I claim as new and desire to secure by Letters Patent the following:

1. A circuit coupler including two coupling members carrying complementary contacts; a spring for pressing one of these contacts toward the other; means whereby the coupling members may be positioned in partially separated relation; an insulated plunger carried by one of the coupling members; and a spring structure for pressing said plunger into engagement with the other coupling member when the coupling members are in partially separated relation mechanically to hold the coupling members in substantially fixed relation when partially separated, the spring pressed contact constituting a barrel that receives the latter spring and through whose contacting end the plunger projects.

2. A circuit coupler including two coupling members carrying complementary con-

tacts, one of these contacts upon one of the coupling members being tubular; means whereby the coupling members may be positioned in partially separated relation; and a spring pressed plunger operating in the bore of the tubular contact and engaging the coupling member complementary to that coupling member which carries the aforesaid tubular contact, when the coupling members are in partially separated relation, to hold the coupling members in substantially fixed relation when partially separated.

3. A circuit coupler including two coupling members; a spring pressed tubular element carried by one of the coupling

members; another element in the form of a plug within the bore of the aforesaid element; and means whereby the coupling members may be positioned in partially separated relation, one of the aforesaid elements co-acting with the coupling member complementary to the coupling member that carries this element to hold the coupling members in substantially fixed relation when partially separated.

In witness whereof I hereunto subscribe my name.

HARRY A. DOUGLAS.
